UNITED STATES PATENT OFFICE.

HERMAN DHUSE, OF KENDALL, ILLINOIS.

FOOTBOARD FOR VEHICLES.

SPECIFICATION forming part of Letters Patent No. 640,883, dated January 9, 1900.

Application filed May 13, 1899. Serial No. 716,700. (No model.)

To all whom it may concern:

Be it known that I, HERMAN DHUSE, a citizen of the United States, residing at Kendall, in the county of Kendall and State of Illinois, 5 have invented a new and useful Footboard, of which the following is a specification.

This invention relates to footboards for vehicles, and has for its object to provide a detachable device located within the body of the 10 vehicle in convenient reach of the feet of the driver and adapted to be folded against the dashboard or front end of the body, so as to be out of the way when not required for use.

With these objects in view the present invention consists in the combination and arrangement of parts, as will be hereinafter more fully described, shown in the accompanying drawings, and particularly pointed out in the appended claims.

20 In the drawings, Figure 1 is a perspective view of a portion of a wagon-body having the improved footboard applied thereto. Fig. 2 is a sectional view taken transversely through the footboard. Fig. 3 is a similar view with 25 the footboard in folded position. Fig. 4 is a detail perspective view of one of the hinges separated.

Corresponding parts are designated by like 30 reference characters in all the figures of the drawings.

Referring to the accompanying drawings, 1 designates a portion of a wagon-body and is shown to illustrate more fully the application 35 of the device. The latter comprises a flat footboard 2, supported by a pair of duplicate hinges 3, which are removably connected to the dashboard or front end 4 of the wagon-body.

By reference to Fig. 4 it will be noted that 40 the stationary upright member 5 of the hinge is in the form of a flat strap, having its upper end provided with an angular hook 6 and which is adapted to engage over the upper edge of the dashboard, as clearly shown in 45 Fig. 2. Upon the opposite side of the member and at the lower end thereof there is provided a pair of spaced bearing-ears 7, between which the movable member 8 of the hinge is adapted to be pivoted. This latter member 50 is provided with a segmental lug 9, which projects longitudinally beyond one end of the member and at one side only thereof, the ex-

treme outer end of the lug being flattened, as at 10, to form a stop for the movable member, as will be hereinafter more fully explained. 55 The opposite end of the movable member is provided with a shoulder 11, projecting at the same side of the member as does the lug 9, and the footboard 2 is fastened across the respective faces of the movable members of the 60 two hinges by means of bolts or suitable fastenings 12. The members of the hinges are connected together by seating the lugs 9 between the respective ears 7 of the fixed members and held therebetween by means of 65 pivot-bolts 13, so that the movable members may be folded up against the fixed members, as clearly shown in Fig. 3 of the drawings. By reference to Fig. 2 it will be seen that the angular hook 6 fits snugly the upper edge of 70 the dashboard 4 and the movable member rests flush against the inner face of the board, while the flattened portion 10 of the lug 9 engages against the adjacent flat face of the fixed member, whereby a stop is provided so 75 as to effectually hold the footboard in a horizontal position in convenient reach of the feet of the driver.

To hold the footboard in its folded position against the dashboard 4, as indicated in Fig. 80 3, I have provided each member of the hinges at their opposite ends with oppositely-disposed hooked lugs 14, each pair of which is adapted to be embraced by a ring or link 15, so as to confine the free ends of the movable 85 members to the stationary members, whereby the footboard is effectually held in its folded position. It will be noted that the shoulders 11 embrace the outer edge of the footboard, and the hooked lugs 14 of the movable members are disposed at the outer end of said 90 shoulders, so as to come as near as possible to the hooked lugs of the fixed members, and thereby facilitate the engagement of the rings or links with said hooks. 95

It will be noted that the stationary members of the hinges are not permanently attached to the dashboard, but are removably connected thereto by means of the angular hooks 6, so that the footboard may be readily removed from the wagon-body when desired and readily positioned for use without the application of bolts and other fastening devices. Furthermore, it will be understood 100

- that the footboard is preferably of a length to fit snugly between the sides 16 and 17, respectively, of the wagon-body, so as to prevent longitudinal movement of the device, and by reason of the stationary members fitting flat against the dashboard and the angular hooks snugly engaging the upper edge thereof the device is effectually prevented from being jolted about or displaced by the movement of the rider. Also it will be understood that the footboard may be located upon the outer side of the dashboard when so desired, as the angular hooks 6 will fit the upper edge of the dashboard from either side thereof.
- 15 The present device provides an exceedingly simple and durable footboard for vehicles, as the parts are effectively connected together, whereby the loss or displacement thereof is effectually prevented, and the device may be readily positioned as a whole to the dashboard of a wagon without the employment of bolts or other fastening devices.

Changes in the form, proportion, size, and the minor details of construction within the scope of the appended claims may be resorted to without departing from the spirit or sacrificing any of the advantages of this invention.

What I claim is—

- 30 1. A device of the class described, comprising hinges, and a footboard connected to the movable members thereof, the stationary members being adapted to be connected to the dashboard of a wagon-body and provided with spaced bearing-ears, and the movable members being provided with segmental lugs having flattened faces and adapted to be pivoted between the ears of the respective stationary members, whereby the flattened faces of said ears are adapted to engage the stationary members and thereby form stops to hold the footboard in a horizontal position, substantially as shown and described.

2. A device of the class described, comprising hinges, and a footboard connected to the movable members thereof, the stationary members being adapted to be connected to the dashboard of a wagon-body, hooked lugs provided at the opposite ends of the hinged members, and rings or links adapted to embrace the respective pairs of hooked lugs so as to hold the footboard in its folded position, substantially as shown and described.

3. A device of the class described, comprising a pair of duplicate hinges, and a flat footboard connected to the movable members of the hinges, each stationary member being provided at its upper end with an angular hook adapted to engage the upper edge of the dashboard of a wagon-body and a hooked lug projecting beyond the end of the member, the opposite end thereof being provided with spaced bearing-ears, each movable member having at one end a segmental lug provided at its outer end with a flattened face and adapted to be pivoted between the respective ears of the stationary members, whereby the flat portion of the lug is adapted to engage the stationary member and form a stop, the opposite end of the movable member being provided with a transverse shoulder adapted to embrace the outer edge of the footboard and having an outwardly-projecting hooked lug, and rings or links adapted to embrace the respective pairs of hooked lugs, whereby the footboard may be held in its folded position, substantially as shown and described.

In testimony that I claim the foregoing as my own I have hereunto affixed my signature in the presence of two witnesses.

HERMAN DHUSE.
